ROBERT G. SCHNEE AND FRED W. RILEY, OF CLEVELAND, OHIO, ASSIGNEES TO THE REPUBLIC MAUSOLEUM COMPANY, OF CLEVELAND, OHIO, A CORPORATION OF OHIO.

PROCESS OF PRESERVING REMAINS.

1,120,336.

Specification of Letters Patent.

Patented Dec. 8, 1914.

Original application filed March 20, 1913, Serial No. 755,718. Divided and this application filed September 8, 1913. Serial No. 788,548.

To all whom it may concern:

Be it known that we, ROBERT G. SCHNEE and FRED W. RILEY, citizens of the United States, residing at Cleveland, in the county of Cuyahoga and State of Ohio, have invented a certain new and useful Improvement in Processes of Preserving Remains, of which the following is a full, clear, and exact description, reference being had to the accompanying drawings.

This invention relates to methods or processes of preserving remains, this application being a division of application No. 755,718, filed March 20, 1913.

It is the general purpose of this invention to provide a process for preserving the remains within a crypt or compartment by maintaining within such crypt or compartment a dry, germicidal atmosphere, whereby the remains will be desiccated, through their contact with such atmosphere, and the formation and discharge of liquids of decomposition will be prevented.

Referring to the drawings forming part hereof, Figure 1 represents a vertical sectional view through a mausoleum of the general character disclosed in our application aforesaid; Fig. 2 a perspective view of one of the disinfecting cartridges placed within each crypt or compartment of the mausoleum; and Fig. 3 a similar view of one of the cartridges or containers for the moisture-absorbing material.

In carrying out our invention, we place within the crypt or compartment containing the remains a sufficient number of the moisture-absorbing receptacles to secure the absorption of all moisture given off from the remains into the atmosphere and to maintain such atmosphere dry within the crypt or compartment. We also place within each crypt or compartment a sufficient number of disinfecting cartridges or containers to saturate the atmosphere with a germicidal gas over a long period of time—sufficient to cover the complete desiccation of the remains by the action of the moisture absorbent. In the case of a mausoleum containing a number of crypts or compartments, each crypt or compartment is hermetically sealed from every other crypt or compartment; but, in the event of failure, through any unforeseen circumstance, of the process to overcome marked decomposition, which

is in rapid progress at the time of interment, 55 with the production of large quantities of gas sufficient to produce pressure within the crypt or compartment, means are provided for venting each crypt or compartment without, however, enabling the external atmosphere to have access thereto and without the discharge of the escaping gases into any other crypt or compartment.

At any suitable place within the crypt or compartment we place a number of the moisture-absorbent cartridges or containers, such as shown in Fig. 3. These cartridges or containers may be made of tin or other sheet metal and are provided each with a cover which can be conveniently removed to expose the contents thereof. For the moisture-absorbing material, calcium oxide is preferred.

For the germicidal agent, formaldehyde is preferred, and this is preferably introduced into the crypt or compartment in the shape of a cartridge consisting of an absorbent, such as asbestos, which is saturated with a solution of formaldehyde gas. By saturating the absorbent with the solution, the spilling of the same is prevented, and by inclosing the saturated absorbent within a sheet metal container, the gas is not given off into the atmosphere until such time as its use is desired. When this time arrives, 85 the top of the casing may be perforated by any suitable tool, the perforations allowing of the gradual escape of the gas, over a long period of time, into the atmosphere to be saturated. A sufficient number of these 90 cartridges will be inserted into the crypt or compartment to maintain the atmosphere therein in a germicidal condition as long as may be necessary.

In the drawings, to which reference has 95 been made hereinbefore, 1 denotes the floor and 2 the roof of a mausoleum. This roof will be provided with a suitable number of cross-draft flues, one of which is indicated at 3, these being connected with the frost space 100 4 usual in buildings of granite and cement construction.

In the drawings, a single double tier of crypts is shown; but it will be evident that any suitable number of tiers may be provided, according to the dimensions of the mausoleum. Each crypt 5, as will be apparent from the drawings, is independent of

every other crypt, and is provided with a trapped vent 6 which is adapted to permit of the escape of any gases from within the crypt while preventing gases entering the same from without. A trapped vent of the character shown in our application 755,718 5 may be employed for this purpose.

The casket 7 is shown as resting upon cross rods 8 supported by ledges 9 projecting upwardly from the bottom 10 of the crypt. The space beneath these rods provides a convenient location for the cartridges 11 which contain the moisture absorbent. These cartridges, when ready for use, may be opened by stripping back the cover 11^a by means of a key, in a well-known manner. The cartridges 12 containing the germicidal agent may be supported in any other convenient place, within the 15 crypt, as on the cross rods 8, the sheet metal tops of the receptacles being perforated in the manner shown in Fig. 2, to permit the gradual escape of the gas. The remains may be exposed to the atmosphere within the 20 crypt in any convenient manner, as by removing the lid of the casket, as indicated in the drawings. A single disinfecting cartridge, if made in about the proportions indicated in the drawings, will be amply sufficient to furnish all the disinfecting gas 25 necessary to maintain a germicidal atmosphere within the crypt throughout the entire period required for the desiccation of the remains. Should any gases of decomposition 30 be evolved, such gases will be neutralized by the germicidal gas; under ordinary conditions, however, no such gases will be evolved, since decomposition is prevented 35 and the remains are thoroughly desiccated.

40 From the foregoing, it will be apparent that we have produced a method or process whereby a dry, sterilizing atmosphere will be maintained within a crypt or compartment, and for a length of time sufficient to 45 completely dry or desiccate the remains without the production and discharge of liquids of decomposition, and without the escape of noxious gases. It will also be evident that, by our process, decomposition 50 is normally prevented and that, in any event, such decomposition will be reduced to a minimum. It will also be evident that the foregoing process is entirely 55 automatic in operation and that the agents entering into such process are contained within each crypt or compartment. Furthermore, these results are obtained without the use of an extraneous agent and at a comparatively slight expense.

60 Having thus described our invention, what we claim is:—

1. The process of preserving remains which consists in inclosing the same within a receptacle which is sealed against the entrance of the external atmosphere, charging 65

from a point within the receptacle the atmosphere therein with a germicidal agent, and automatically removing the moisture from the atmosphere within such receptacle, the charging of the atmosphere with the germicidal agent and the removal of the moisture therefrom continuing throughout the period required for the complete desiccation of the remains. 70

2. The process of preserving remains which consists in inclosing the same within a receptacle which is sealed against the entrance of the external atmosphere, charging from a point within the receptacle the atmosphere therein with a germicidal agent, 75 automatically removing the moisture from the atmosphere within such receptacle, the charging of the atmosphere with the germicidal agent and the removal of the moisture therefrom continuing throughout the period required for the complete desiccation of the remains, and allowing the gaseous contents of the receptacle to escape from time to time should the pressure become excessive. 80

3. The process of preserving remains which consists in inclosing the same within a receptacle which is sealed against the entrance of external gases, placing within said receptacle a germicidal liberator whereby the atmosphere within the receptacle will be charged with such gas, and automatically removing the moisture from the atmosphere within such receptacle, the charging of the atmosphere with the germicidal gas and the removal of the moisture therefrom 85 continuing throughout the period required for complete desiccation of the remains. 90

4. The process of preserving remains which consists in inclosing the same within a receptacle which is sealed against the entrance of the external atmosphere, producing from a point within the receptacle a germicidal gas whereby the atmosphere within the receptacle is saturated with such gas, and removing, through a drying agent placed within the receptacle, the moisture from such atmosphere, the charging of the atmosphere with the germicidal gas and the removal of the moisture therefrom continuing throughout the period required for complete desiccation of the remains. 105 110

5. The process of preserving remains which consists in inclosing the same within a receptacle which is sealed against the entrance of the external atmosphere, discharging a germicidal agent from a cartridge placed within the receptacle, whereby the atmosphere is charged with such germicidal agent, and drying the atmosphere within the receptacle by a drying agent contained therein, the charging of the atmosphere with the germicidal gas and the removal of the moisture therefrom continuing throughout the period required for complete desiccation of the remains. 120 125

6. The process of preserving remains which consists in inclosing the same in a receptacle which is sealed against the entrance of the external atmosphere, charging 5 the atmosphere in said receptacle with gaseous formaldehyde liberated within the receptacle, and subjecting the atmosphere to the drying action of calcium oxide within the receptacle, the gaseous formaldehyde being gradually discharged into the atmosphere throughout a prolonged period of 10

time sufficient for desiccation and the calcium oxide being present in sufficient quantity to complete the desiccation of the remains.

In testimony whereof, we hereunto affix 15 our signatures in the presence of two witnesses.
